UNITED STATES PATENT OFFICE.

HERMAN G. WEBER, OF APPLETON, WISCONSIN, ASSIGNOR OF ONE-HALF TO AMERICAN LAKES PAPER COMPANY, OF CHICAGO, ILLINOIS, A CORPORATION OF DELAWARE.

COATING MACHINE.

Application filed February 2, 1925. Serial No. 6,165.

This invention relates to coating machines but more particularly to such as are adapted for applying paste or gum to paper bags, envelopes, and the like, and has for its primary object to provide a more uniform application of the coating material.

Further important objects of my invention are to prevent dry spaces on the feed roller produced by the presence of foreign material or lumps in the vicinity of this roller, to agitate the coating material, to save labor, and in general, to provide a simplified and improved coating mechanism.

The particular embodiment of my invention which I have selected to illustrate the principles thereof forms a part of the gumming mechanism of a paper bag machine, but it will be readily evident that the novel elements of this device are equally applicable to any type of coating mechanism.

Referring to the drawing,

Fig. 1 is a central, vertical section of the coating mechanism, and

Fig. 2 is a transverse, vertical section on the line 2—2 of Fig. 1.

In the drawings, the supply of coating material is held in a suitable receptacle as 5, and this material is removed therefrom by a feed roller as 6, which in the present embodiment directly applies this material to a gumming die as 7. The roller is preferably mounted in eccentric bearings as 8, which enable the position of this roller to be adjusted to provide different thicknesses of coating layer. The method of adjusting this roller forms no part of the present invention and, therefore, need not be described in detail.

The portion of the periphery of the roller 6 which faces the receptacle 5 forms a part of one wall of this receptacle and is constantly in contact with the coating material therein. This roller rotates in the direction indicated by the arrow in Fig. 1. The thickness of the layer of coating material withdrawn from the supply receptacle by the roller depends upon the distance of the periphery of the roller from the upturned edge 9 of the receptacle wall. Lumps of the coating material or foreign matter which are present in the receptacle tend to collect at this point and these act to remove the coating material from the roller as it leaves the receptacle. Various devices have been

provided to effect the removal of these obstructions, but these generally have been manually operated. Considerable difficulty is encountered in getting the operator to use such devices and the results have not been satisfactory.

In the present invention I have provided an automatic device which not only effectively removes all obstructions from the vicinity of the periphery of the roller as such roller leaves the supply receptacle but constantly agitates the material in the receptacle and uniformly spreads the same over the roller. This device comprises a revoluble screw or worm as 10, which extends transversely of the receptacle adjacent to the roller 6 and the upturned edge 9 of the receptacle. In the present embodiment this screw is directly driven from the main shaft 11 of the roller 6 by means of gears 12 and 13. This screw is preferably of steep pitch and acts to continuously push the lumps of foreign matter longitudinally of the roller toward the end wall of the receptacle. I prefer to shape the upturned edge of the receptacle wall to substantially fit about the screw in the manner indicated at 14 in Fig. 1.

In the foregoing description it will be evident that my improved coating mechanism operates entirely automatically and is not dependent upon the will of the operator. A uniform distribution of the coating material on the periphery of the feed roller is insured at all times and constant agitation of the coating material is provided. The mechanism is simple in construction and is applicable to practically any form of coating mechanism in which the coating material is withdrawn from a supply receptacle by means of a feed roller.

I am aware that the form and arrangement of the parts may be considerably varied without departing from the spirit of my invention, and I reserve the right to make all such changes as fairly fall within the scope of the following claims.

I claim as my invention:

1. In a coating device, the combination of a receptacle for coating material, a revoluble feed roller for withdrawing the coating material from said receptacle so positioned relatively to said receptacle that a wall of the latter co-operates with the pe-

riphery of said roller to determine the thickness of the layer of coating material withdrawn from the receptacle by the roller, and means for abstracting lumps tending to lodge between the periphery of said roller and said wall.

2. In a coating device, the combination of a receptacle for coating material having a fixed wall formed with a free horizontal edge, a revoluble feed roller dipping into said receptacle and forming a moving wall of the latter, the periphery of said roller co-operating with said free edge to determine the thickness of the layer of coating material withdrawn by said roller, and means normally wholly immersed in the coating material operative to continuously abstract lumps tending to lodge in the pass between said roller and said fixed wall.
3. In a coating device, the combination of a revoluble feed roller, a receptacle for coating material formed with an up-turned end wall terminating in a free edge parallel with and narrowly spaced from the periphery of said roller and co-operating with the latter to determine the thickness of the layer of coating material withdrawn from said receptacle by said roller, and a revoluble member in said receptacle located behind

said end wall and closely adjacent to the free edge of the latter and the periphery of said roller operating to agitate the material in said receptacle adjacent to said roller, to withdraw lumps tending to clog the pass between said end wall and roller, and to effect a uniform distribution of the coating material on the periphery of said roller.

4. In a coating device, in combination a receptacle for holding a supply of coating material, a revoluble feed roller for withdrawing said material therefrom, and a substantially helical member revoluble in said receptacle adjacent said roller to agitate the material therein and provide a uniform distribution of said material on the periphery of said roller.

5. In a coating device, in combination a receptacle for holding a supply of coating material, a revoluble feed roller operating therein to withdraw said material therefrom, a revoluble screw member mounted in said receptacle adjacent said roller with its axis substantially parallel with the axis of said roller to cause a movement of said material longitudinally of said roller and means for actuating said screw.

HERMAN G. WEBER.
